UNITED STATES PATENT OFFICE.

LEWIS ELSWORTH VAN EVERY, OF HAMPTON, IOWA.

TONGS.

Application filed July 25, 1924. Serial No. 728,153.

To all whom it may concern:

Be it known that I, LEWIS E. VAN EVERY, a citizen of the United States, residing at Hampton, in the county of Franklin and State of Iowa, have invented certain new and useful Improvements in Tongs, of which the following is a specification.

This invention relates to handling implements of the tong type, and has for its object, in a manner as hereinafter set forth, the provision of a pair of tongs particularly constructed for use in handling ice cream cans or other articles of a similar or bulky nature.

15 A further object is the provision, in a manner as hereinafter set forth, of a pair of tongs, so constructed that upon the up or downward movement of a single handle carried by the tongs, the said tongs will automatically open or close, to grasp or release the object to be handled.

20 A still further object of the invention is the provision of a pair of tongs, in a manner as hereinafter set forth, so constructed that upon the upward movement of the handle carried thereby, the tong members will be drawn in tightly against the object to which they are applied.

The final object of the invention is the 25 provision, in a manner as hereinafter set forth, of a pair of tongs having few moving parts, of simple structure, light, durable, yet inexpensive to manufacture.

The invention will be best understood 30 from a consideration of the following detailed description taken in connection with the accompanying drawings forming part of this specification, with the understanding that the invention is not confined to 35 any strict conformity with the showing of the drawings, but may be changed and modified so long as such changes and modifications mark no material departure from the salient features of the invention as expressed in the appended claims.

40 In the drawings:—

Figure 1 is a side elevation of the device embodying my invention.

Fig. 2 is a side elevation thereof, and

50 Fig. 3 is a section taken on the line 3—3 of Fig. 1.

Referring now to the drawings in detail, wherein like numerals of reference indicate corresponding parts throughout the several 55 views of the drawing, there is shown a pair of cross members 1, each formed of a broad

flat band of steel or iron. As is clearly shown, the flat surface of these members are laid together and secured by a rivet 2 at a point above their central point. Below the pivot point, each member is given a half twist inward at the point 3 bringing the flat surfaces of the members face to face as at 4. The lower end of each of the members below the pivot point are bowed outwardly as shown, bringing the lower ends towards one another, which ends are turned upwardly and inwardly to form the hooks 5, which hooks are not sharpened, but are the same width as the member 1.

60 The upper end of each of the members 1 above the pivot point, are traversed by a substantially elongated slot 6 extending from the upper end of the member to a point approximately midway between that end and the pivot point, which slot is adapted to receive between its inner faces, a roller member 8 carried by a bolt 9.

65 Connecting the upper free ends of the members 1, is an actuating member 10 formed of a piece of rectangular material, bent upon itself and split along its bent portion from either end inwardly to the points 11 to provide a pair of opposed engaging arms 12, and 13, which arms are positioned 70 one on either side of the adjacent member 1, and are carried and secured in position upon the rivet 9, as clearly shown in Fig. 3.

75 A handle member 15 is provided by looping a section of cylindrical material appropriate for this purpose and passing the ends beneath the central portion of the actuating member 10, between the points 11—11, and bringing them out upon opposite sides as is clearly shown in Fig. 1 and then bending the end 16 about the adjacent portion of the loop, as shown.

80 From the foregoing description, it may be seen that when the actuating member is pressed downward, the roller carried between the arms 12 and 13 upon the bolt 9, rides down the slot 6 forcing out the upper ends of the members 1, and consequently opening the hooks 5 at the lower end. When the object to be lifted has been engaged by the hooks 5, the handle member 15 is grasped and lifted upwardly drawing upwardly the actuating links 10 and reversing the action just described to close the lower ends drawing them in, to tightly engage the object.

85 As has been said, the hook members 5

are broad being of the same width as the width of the members from which they are formed, insuring a better engagement with the object to be grasped, as for example, 5 should it be desired to lift a metal container such as is used to store ice cream in, the hooks 5, being broad, insure a better engagement with the flange surrounding the can than would be the case if they were 10 sharpened like the type of tongs commonly in use.

What I claim is:

1. In a pair of tongs, a pair of crossed 15 grappling members, each having a longitudinal slot in its upper end and inturned at its lower end to provide a hook, a pivot connection between said members, an actuating member, means extending through each end of said actuating member and through 20 said slot, for retaining said actuating member in shiftable engagement with the grappling members, and a handle carried by said actuating member.

2. In a pair of tongs, a pair of crossed 25 grappling members, each having a longitudinal slot in its upper end and inturned at its lower end to provide a hook, a pivot connection between members, an actuating member, means extending through each end 30 of said actuating member, and through said slot, for retaining said actuating member in shiftable engagement with the grappling member, rollers carried by said means and travelling against the opposed walls of said 35 slots, during the operation of the actuating member, and a handle carried by said actuating member.

3. In a pair of tongs, a pair of crossed 40 flat grappling members, each having a longitudinal slot in its upper end, and inturned at its lower end to provide a hook, a pivot connection between said members, said members below the pivot point, being given a half twist causing the width of the lower 45 portion to be disposed at right angles with respect to the upper portion, an actuating member, means extending through each end of said actuating member and through said slot for retaining said actuating member in 50 shiftable engagement with the grappling members, and a handle carried by said actuating member.

4. In a pair of tongs, a pair of crossed 55 grappling members each having a longitudinal slot in its upper end and inturned at its lower end to provide a hook, a pivot connection between said members, an actuating member formed of a rectangular piece of material bent upon itself and split from 60 each end inward a short distance along its bent portion providing a central cross connecting portion and opposed end arms, said

arms adapted to be positioned one on either side of the upper end of the adjacent grappling member, means extending through 65 said opposed arms at each end of the actuating member and through said slot for retaining said actuating member in shiftable engagement with the grappling members, and a handle carried by said actuating member. 70

5. In a pair of tongs, a pair of crossed grappling members each having a longitudinal slot in its upper end and inturned at its lower end to provide a hook, a pivot 75 connection between said members, an actuating member formed of a rectangular piece of material bent upon itself and split from each end inward a short distance along its bent portion providing a central cross connecting portion and opposed end arms, said arms adapted to be positioned one on either side of the upper end of the adjacent grappling member, means extending through 80 said opposed arms at each end of the actuating member and through said slot for retaining said actuating member in shiftable engagement with the grappling members, rollers carried by said means and travelling against the opposed wall of said slot the 85 operation of the actuating member, and a handle carried by said actuating member. 90

6. In a pair of tongs, a pair of crossed grappling members each having a longitudinal slot in its upper end and inturned at 95 its lower end to provide a hook, a pivot connection between said member, an actuating member formed of a rectangular piece of material bent upon itself and split from each end inward a short distance along 100 its bent portion providing a central cross connecting portion and opposed end arms, said arms adapted to be positioned one on either side of the upper end of the adjacent grappling member, means extending through 105 said opposed arms at each end of the actuating member and through said slot for retaining said actuating member in shiftable engagement with the grappling members, rollers carried by said means and travelling against the opposed walls of said slot during 110 the operation of the actuating member, and a handle member formed to provide a loop and having its free end passed in opposite directions beneath said central connecting portion of the actuating member and further having its ends brought up at the ends of said central connecting portion and secured by twisting about the adjacent 115 loop portion. 120

In testimony whereof, I affix my signature hereto.

LEWIS ELSWORTH VAN EVERY.
